COMBINED LAMP AND RADIO RECEIVING
SET

Daniel J. Crowley, Grosse Pointe, Mich.

Original application December 4, 1936, Serial No.
114,268. Divided and this application June 3,
1939, Serial No. 277,267

10 Claims. (Cl. 250—14)

This invention relates generally to a combined lamp and radio receiving apparatus and is a division of my copending application Serial No. 114,268, filed December 4, 1936.

One of the principal objects of this invention resides in the provision of a radio receiver comprising a standard circuit of proven efficiency having the several instrumentalities thereof ingeniously arranged in compact groups in different portions of a lamp in a manner to insure efficient performance of the radio receiving circuit and at the same time render it possible to obtain wide variations of artistic lamp designs.

Another advantageous feature of the present invention resides in the provision of a combined lamp and radio receiving set embodying improved means for actuating the several controllable instrumentalities of the radio receiving circuit, such as the variable condensers and the rheostat for controlling the volume of the radio receiving set.

A further object of the present invention resides in the provision of a combined lamp and radio receiving set wherein the variable condensers are housed in the base of the lamp in a manner to occupy the minimum height and wherein the condensers are operated as a unit by means of a control conveniently positioned with respect to the base of the lamp.

The foregoing, as well as other objects, will be made more apparent as this description proceeds, especially when considered in connection with the accompanying drawings, wherein:

Figure 1 is a perspective view of a lamp embodying radio receiving apparatus in accordance with the present invention and having certain parts broken away for the sake of clearness;

Figure 2 is a cross sectional view taken substantially on the plane indicated by the line 2—2 of Figure 1;

Figure 3 is a cross sectional view taken substantially on the plane indicated by the line 3—3 of Figure 1;

Figure 4 is a cross sectional view taken substantially on the plane indicated by the line 4—4 of Figure 1;

Figure 5 is a cross sectional view taken substantially on the plane indicated by the line 5—5 of Figure 1;

Figure 6 is a cross sectional view taken substantially on the plane indicated by the line 6—6 of Figure 1;

Figure 7 is a cross sectional view taken substantially on the plane indicated by the line 7—7 of Figure 1;

Figure 8 is a fragmentary cross sectional view taken substantially on the plane indicated by the line 8—8 of Figure 6;

Figure 9 is a cross sectional view taken substantially on the plane indicated by the line 9—9 of Figure 6;

Figure 10 illustrates a diagram of one type of radio receiving circuit that may be employed in the lamp construction featured in the above figures;

Figure 11 is a side elevational view, partly in section, of a modified form of combined lamp and radio receiving set;

Figure 12 is a cross sectional view taken substantially on the plane indicated by the line 12—12 of Figure 11;

Figure 13 is a cross sectional view taken substantially on the plane indicated by the line 13—13 of Figure 11;

Figure 14 is a cross sectional view taken substantially on the plane indicated by the line 14—14 of Figure 11;

Figure 15 is a fragmentary vertical sectional view through a portion of the base of the lamp featuring the means provided for operating the variable condensers in the base of the lamp;

Figure 16 is a fragmentary sectional view through the base portion of a combined lamp and radio receiving set constituting still another embodiment of this invention.

Referring first to the embodiment of the invention illustrated in Figures 1 to 10, inclusive, it will be noted that there is illustrated in Figure 1, a relatively small artistic table lamp 30 having a base 31 supporting a vertical pedestal 32 and having a shade 33 carried by the pedestal 32 at the upper end thereof. In the present instance, one portion of the radio receiving apparatus is housed within the base 31, another portion is housed in the vertical pedestal 32 and still another portion is arranged within the lamp shade 33.

Although it is to be understood that the specific parts of the radio receiving apparatus housed in the aforesaid sections of the lamp may vary to suit existing conditions, nevertheless, for the purpose of illustration, I have resorted to the following arrangement. Upon reference to Figure 10, it will be noted that the radio receiving circuit, selected herein for the purpose of illustrating the present invention is, of the superheterodyne type and the parts thereof contained in the area defined by the character A are housed within the base 31 of the lamp, while the parts of the circuit contained in the area defined by the

character B are located in the vertical pedestal 32 of the lamp, and the instrumentalities of the circuit contained in the area defined by the character C are located in the shade 33 of the lamp.

In order to illustrate the ingenious manner in which the various parts of the radio receiving circuit are compactly arranged in the several sections of the lamp, reference will be briefly made to the various units of the receiver included in the areas defined by the characters A, B and C. Referring again more particularly to Figure 10, it will be noted that the base 31 of the lamp houses one stage of radio frequency including an RF coil 34 and a tube 36 of the 6 K7 type. The base 31 of the lamp also includes the first detector and oscillator stage including a detector coil 37, a variable condenser 38 and a pentagrid converter 39. Also in the base 31 of the lamp is the intermediate stage including a variable condenser 40 for tuning the primary winding of the intermediate coil, and a second variable condenser 41 for tuning the secondary winding of the intermediate coil. In addition, the base 31 of the lamp includes the oscillator coil 42 and a variable condenser 43 for tuning the primary winding of the same.

In the present instance, the vertical pedestal 32 of the lamp encloses the tube 44 for the intermediate stage, a second detector coil 45, variable condensers 46 for respectively tuning the primary and secondary of the second detector coil, and the second detector tube 47. The power pack defined by the character C is housed within the lamp shade 33 and includes a full wave rectifier tube 48 and an amplifier 49 comprising a speaker 50 and an audio tube 51. The problem of compactly arranging the several parts of the radio receiving apparatus in the base and pedestal of the lamp without the danger of overheating the insulation associated with certain of said parts, is solved by locating the power pack in the shade of the lamp where the heat radiated by the rectifier and amplifier tubes may be readily dissipated.

One of the principal features of the present invention which contributes materially to compactly arranging in the base 31 of the lamp the instrumentalities of the receiving circuit contained in the area A consists in the unique arrangement of the variable condensers and the manner in which the latter are operated. Upon reference to Figure 6 of the drawings, it will be noted that the variable condensers 35, 38 and 43 are each formed of two complementary sections and the latter are symmetrically distributed in the base with respect to the vertical center line of the lamp. By forming each of the condensers of two complementary sections and by distributing the sections in the above manner, it is possible to minimize the height of the base of the lamp so that the latter will not present a cumbersome or bulky appearance. Each of the condensers is preferably identical in construction and comprises a pair of stators 52 and a pair of rotors 53 rotatably mounted with respect to the stators in a manner to be presently set forth.

In order to simplify the control of the radio receiving apparatus, common means is provided for simultaneously rotatably adjusting the rotors 53 of each of the condensers 35, 38 and 43. The manner in which the foregoing is accomplished will be understood upon referring to Figures 6 to 9, inclusive, wherein the reference character 54 designates a fiber driving gear mounted for rotation substantially centrally of the base 31 of the lamp and arranged in mesh with the three gears

designated in Figure 7 by the reference characters 55, 56 and 57. The gear 55 is secured to the shaft 58 of one of the rotors of the variable condenser units 3, while the gear 56 is secured to the 10 rotor shaft 59 of one of the rotors of the variable condenser unit 38, and the gear 57 is secured to the rotor shaft 60 of one of the rotors of the condenser unit 43. Thus, it will be observed that one rotor shaft of each pair is driven by the drive gear 54 and, in order to impart the same degree of rotation to the other rotor shaft of each pair, suitable gears 61 are secured to the latter shafts in mesh with the gears 55, 56 and 57 respectively. The gears 61 are of the same size as the gears 15 55 to 57, inclusive, so as to insure simultaneous movement of the rotors at the same rate of speed, and the axes of the gears 61 are so located that the latter gears do not mesh with the drive gear 54. Adjustment of the rotors of the several variable condensers is effected through the gears by means of a control 62 having an arm 63 secured as at 64 to the drive gear 54 and extending laterally outwardly from the latter gear through an arcuate slot 65 formed in the side wall of the base 20 adjacent the bottom of the latter. The other extremity of the arm 63 is provided with an upwardly extending pointer 66 and a knob 67 is secured to the pointer in a position to be conveniently grasped by the operator. The pointer 66 is for the purpose of indicating the usual indicia applied to a band 68 which, in turn, is secured to the side wall of the base above the slot 65.

Referring now more in detail to the particular construction of the lamp selected herein for the purpose of illustration, it will be noted that the same comprises a base plate 69 secured to an auxiliary non-metallic base 70 through the medium of the fastener elements 71. The auxiliary base 70 is positioned in spaced relation to the base 69 through the medium of the spacers 72 surrounding the fastener elements 71 and of sufficient length to provide the space 73 between the two plates required to house the gearing previously referred to as operating the rotors of the variable condensers 35, 38 and 43. Upon reference to Figure 9, it will be noted that a fastener element 74 serves to secure the central portion of the base plate 69 to a disc 75 held in spaced relation to the plate 69 by means of a spacer 76 located within the space 73 and having a length approximating that of the spacers 72 so as to support the disc 75 in the plane of the auxiliary base plate 70. In the present instance, the spacer 76 is provided with a cylindrical exterior surface forming a journal for the drive gear 54 of the variable condenser gear train.

The manner in which the remaining gears of the aforesaid train are mounted is illustrated in Figure 8. In this connection, it is to be noted that Figure 8 shows only the pair of gears 57 and 61 directly associated with the variable condenser 43, and it is to be understood that the remaining pairs of gears are mounted in an identical manner. In detail, the gears 57 and 61 are secured to the lower ends of the variable condenser rotor shafts 60 and 61', respectively. These shafts are suitably journalled in metallic inserts 77 secured in the auxiliary base plate 70 and the portions of the shafts extending above the auxiliary base form supports for the complementary variable condenser rotors 53. The rotors 53 are provided with bushings 79 secured to the rotor shafts and carrying the rotor plates 80. The rotors 53 are grounded by spring metal fasteners 83 having the outer ends fixedly se-

cured to the auxiliary base 70 and having the inner ends disposed between the latter base and the lower ends of the bushings 79. As shown in Figure 8, the inner ends of the fingers 83 are shaped to constantly urge the rotor shafts in an upward direction and thereby maintain the required relationship between the rotor blades 80 and the cooperating stator blades of the variable condenser. Thus, it will be apparent that each of the variable condensers, employed in the construction, is formed of two complementary sections cooperating to afford substantially double the capacity of a single condenser unit of the same height. In other words, the above construction renders it possible to house condensers of the required capacity in a relatively small vertical space and this is of extreme importance in the present illustrative embodiment of the invention, due to the limited vertical space available in the base 31 of the lamp.

Upon reference to Figures 3, 5 and 6, it will be noted that provision is made to shield certain parts of the radio receiving circuit from other parts of this circuit. This is accomplished herein by arranging the vertical shields 84 in the base 31 having the lower ends extending through the auxiliary base plate 70 and secured to the underside of the latter by means of the horizontal plates 85. The particular number of shields and the arrangement of the latter in the base 31 will, of course, depend upon the nature of the portions of the circuit housed in the base. With the specific arrangement shown in Figures 1 to 10, inclusive, the shields 84 are preferably located in the manner clearly illustrated in both of Figures 5 and 6 to shield from each other the several parts of the radio receiving circuit shown in these figures.

Cooperating with the base plate 69 to form a housing for all of the parts of the radio receiving apparatus in the base 31 of the lamp is a casing 85' secured at the lower end to suitable brackets 86 by fastener elements 87 having the additional function of securing the indicia band 68 to the side wall of the casing. The brackets 86 are secured to the auxiliary base plate 70 in the manner shown in Figure 8 and the fastener elements 87 are preferably the only means securing the casing 85' in place, with the result that the same may be readily removed when access to the radio receiving parts in the base is desired. The contour of the casing 85' is shown in Figure 1 and as will be observed from this figure, the top wall of the casing is apertured to provide for extending the combined volume and "on" and "off" switch control 33 therethrough. It will, of course, be understood that the knob of this control is readily detachable in order to permit the casing 85' to be removed when desired. The top wall of the casing 85' is also centrally apertured, as at 89, to receive a bushing 90 having the lower end sleeved over the disc 75 and permanently secured to the latter. The upper end of the bushing 90 projects above the top wall of the casing 85' and is normally concealed by a collar 91 fixedly secured to the casing 85'.

Referring now to the peculiar construction of the pedestal 32 of the lamp, it will be noted that the same comprises two eccentrically arranged tubular sections 92 and 93. The outer tube 92 is formed of two complementary sections for convenience in assembly and the lower end of this tube is sleeved within the collar 91 to seat upon the upper end of the bushing 90, in the manner clearly shown in Figure 1. The complementary

sections of the tube 92 are secured in assembled relation at the lower end by the collar 91 and at the upper end by the closure 94, threadedly secured to the stem 95 projecting into the tube 92 through the closure 94.

The tube 93 is supported within the tube 92 eccentrically with respect to the latter so as to provide the maximum space 96 for the electrical conductors 97 required to connect the instrumentalities of the radio receiving apparatus in the base to the parts of the same in the pedestal and in the shade. In detail, the lower end of the tube 93 is sleeved on an enlargement of the disc 75 in the manner shown in Figure 9, and the upper end of the tube 93 is suitably secured to the lower end of the stem 95. It has been previously stated that the intermediate tube 44 and the second detector tube 47 are located in the pedestal 32 and, in the present instance, are housed in the tubular member 93. In order to permit these tubes to be readily assembled with, or removed from, the tubular member 93, the latter is cut away opposite the tubes in the manner designated by the reference character 99. In this connection, it will be noted from Figure 5 that the bushing 90 is also cut away as at 100 in alignment with the cut-away portion 99 in the lower end of the tubular member 93 so as to completely expose the intermediate tube 44 through the tubular member 93.

Referring now to the construction of the lamp shade 33, it will be noted that a housing 101 is secured to the upper end of the stem 95 within the shade 102 and this housing contains the power transformer 103, together with the associated choke coils forming parts of the power pack or speaker unit assembly. The speaker 50 is supported upon the upper end of the housing within the shade 102 and the cone 104 of the speaker is supported, in the manner shown in Figure 1, directly below the perforated disc 105 forming the top of the shade 102. The above construction is such that the shade 102 also acts as a baffle to prevent the upwardly directed column of air from co-mingling with the downwardly directed column of air, and thereby prevents the cancellation of the bass notes.

Upon reference to Figure 1, it will also be noted that the housing 101 supports the illuminating bulbs 106, and these bulbs are so positioned with respect to the other instrumentalities housed in the shade as to prevent the same from casting a shadow on the shade. The illuminating bulbs 106 are arranged in switch sockets 107 and the latter are connected to the housing through the medium of tubes 108 of sufficient diameter to permit the electrical conductors to be extended therethrough.

In the embodiment of the invention illustrated in Figures 11 to 15, inclusive, I have shown a different arrangement of the several instrumentalities of the radio receiving circuit in the base and pedestal of the lamp. In general, the base 124 contains only the variable condensers of the receiving circuit and the means for actuating the several rotors of the condensers simultaneously. The remaining parts of the radio receiving circuit described in connection with the first form of the invention as being in the base of the lamp are compactly positioned within the pedestal 126, and the latter is divided into three compartments for accommodating these parts. Upon reference to Figure 14, it will be noted that the first detector coil 127, the oscillator coil 128 and the RF coil 129 are located in the compartment 130

and are shielded from one another by the shield 131'. Disposed directly above the compartment 130 is an intermediate compartment 131 and the latter is adapted to house the pentagrid converter 132, the first intermediate tube 133, intermediate coil 134 and the RF tube 135. As shown in Figure 13, the several tubes in the compartment 131 are shielded from one another and from the coil 134 by the shields 136. The upper compartment 132' is shown in Figure 12 as containing a second intermediate coil 137, a second detector tube 138, a second intermediate coil 139 and a second intermediate tube 140. The tubes 138 and 140 are shielded from each other, as well as from the two coils, by means of the shields 141 suitably secured within the compartment 132'. It will be noted from the above that the circuit in the present lamp construction differs from the circuit featured in Figure 10 in that it embodies an additional stage of intermediate frequency.

The variable condensers are exactly the same in construction as defined in connection with the first embodiment of this invention and the gearing for operating the rotors of these condensers is also arranged in the same manner previously described. However, the means for simultaneously operating the several rotors of the condensers is slightly different and this means is shown in Figures 11 and 15 as comprising a ring 142 supported for rotation about the axis of the drive gear 54^a by the rollers 143 secured to the base plate 144 in circumferential spaced relationship. The diameter of the ring is predetermined with respect to the dimension of the base 125 so that peripheral portions of the ring extend through slots 146 in the several sides of the base permitting the ring to be conveniently engaged by the operator from several sides of the base. Upon reference to Figure 15, it will be noted that the ring is secured to the drive gear 54^a by means of a strap 147 so that the rotative movement imparted to the ring will be transferred to the drive gear 54^a and from the latter to the several rotors of the condensers in the same manner described in connection with the first embodiment of this invention. With this construction, the condensers may be controlled from any one of a number of sides of the base and the volume may be regulated by a control 88^a similar to the one shown in Figure 1 of the drawings. Attention is called to the fact that in this embodiment, the wave indicating band 142' is secured to the ring 142 for rotation as a unit with the latter to register the indicia thereon with a fixed pointer 143' extending into the window 144'.

Referring now to the embodiment of the invention illustrated in Figure 16, it will be noted that the condensers 150 are distributed in the base 151 of the lamp in the same manner illustrated in the first described form of the invention and the rotors of the condensers are simultaneously rotated relative to the stators by means of a central driving gear 152 rotatably supported on the annular wall 153 of the compartment 154. The central driving gear 152 meshes with suitable pinions 155 which, in turn, are secured to the rotor shafts of the condensers, with the result that these shafts are simultaneously rotated upon rotation of the central driving gear 152. In the present instance, rotative movement is imparted to the driving gear 152 by means of a ring 156 having a diameter slightly less than the diameter of the side wall 157 of the base and connected to the driving

gear 152 by means of the spokes 158. The ring 156 is, of course, concentrically arranged with respect to the axis of rotation of the gear 152 and is made accessible for rotation exteriorly of the base by means of a control ring 159 secured to the ring 156 and projecting laterally outwardly through the annular space 160 provided in the side wall 157 of the base.

It will be observed from Figure 16 that the annular space 160 is provided by forming the base 151 of two sections and by securing the sections in vertical spaced relation to each other through the medium of the spacers 161. The upper ends of the spacers are shown in Figure 16 as engaging the undersides of suitable lugs 162 permanently secured to the upper section of the base 151 and the lower ends of the spacers abut the bottom wall of the lower section of the base. In the present instance, the spacers are in the form of tubes for receiving suitable fastener elements 163 and the latter serve to effectively clamp the two sections of the base in assembled relationship.

It will also be observed from Figure 16 that the combined volume control and "off" and "on" switch 164 is supported in the base 151. This device is operated by means of a ring 165 surrounding the lower end of the pedestal 166 and supported on the top wall of the base for rotation about the axis of the pedestal. The ring 165 is held against axial displacement relative to the pedestal by means of an annular radially outwardly extending flange 166' provided at the lower end of the pedestal and adapted to extend over an annular inwardly extending flange 167 on the ring 165. As a result, the ring is held in assembled relationship with the lamp and may be rotated about the axis of the pedestal. In the present instance, the ring 165 is operatively connected to the device 164 through the medium of suitable gearing. As shown, a gear 168 is rotatably supported on the annular side wall 153 of the compartment 154 and is connected to the ring 165 for actuation thereby by means of a pin 169. The device 164 is provided with an operating shaft 170 having a pinion 171 secured thereto in mesh with the gear 168 so that rotation of the ring 165 effects a rotation of the operating shaft 170 to not only control the volume of the radio receiving set, but to also control the circuit supplying electrical energy to the radio receiving set.

Although a number of different embodiments of this invention have been described somewhat in detail, nevertheless, it will be noted that each modification contemplates installing a complete radio receiving apparatus in a lamp in such a manner that the same does not appreciably restrict the design of the lamp or render the same cumbersome in appearance. In other words, in each of the several embodiments of this invention, the instrumentalities of the radio receiving apparatus are ingeniously arranged to permit the same to be housed in the minimum of space and this is of particular importance from the artistic point of view. It will also be noted that in each embodiment of the invention, the rectifier and amplifier tubes are located in the shade assembly of the lamp so that the heat generated by these tubes will not destroy any of the parts of the radio receiving apparatus sensitive to heat and will not interfere with the compact arrangement of these parts. In addition to the foregoing, it will be noted that I have provided novel control means for the several instrumentalities of

the radio receiving apparatus and that this means is of such a nature as to permit the same to be cleverly worked into the design of the lamp.

What I claim as my invention is:

1. In a radio receiving set, a base unit composed of upper and lower sections spaced from each other to provide a circumferentially extending slot therebetween, a radio receiving circuit including a variable condenser having a rotatably adjustable part located in the base unit, a ring rotatably supported between the sections and having a laterally extending annular portion projecting through the circumferentially extending slot between the sections of the base unit, and means operatively connecting the ring to the adjustable part of the condenser.

2. In a radio receiving set, a base unit composed of upper and lower sections spaced from each other to provide clearance therebetween, a radio receiving circuit including a plurality of variable condensers having rotatably adjustable parts housed in the base in spaced relation to each other around the vertical center line of the base, a member rotatably supported on the vertical center line aforesaid and operatively connected to each of the rotatably adjustable parts for simultaneously actuating the latter, a ring rotatably supported in the space provided between the sections of the base unit in concentric relation to the axis of rotation of said member and having an annular portion projecting outwardly beyond the side wall of the base unit for convenient manipulation, and means operatively connecting the ring to said member.

3. In a radio receiving set, a base unit having a supporting plate and a casing supported above the plate to provide a space therebetween, a radio receiving circuit including a plurality of variable condensers having rotatably adjustable parts supported in the base in spaced relation around the vertical center line of the base, a pinion secured to each of the rotatably adjustable parts, a driving gear rotatably supported on the vertical center line aforesaid and meshing with each of the pinions, a control member rotatably supported in the space between the supporting plate and casing and extending outwardly beyond the side wall of the casing for actuation by the operator, and means operatively connecting the control member to the driving gear.

4. In a radio receiving set, a base unit having a slot through the side wall thereof, a radio receiving circuit housed in certain of the units aforesaid of the lamp and embodying a plurality of variable condensers housed in the base unit of the lamp, each of the variable condensers comprising a plurality of sections connected together to afford the combined capacitance of the sections and each section embodying a rotatably adjustable part distributed in the base unit in concentric relation to the vertical center line of the base, a member supported for rotation on the vertical center line aforesaid and operatively connected to each of the rotatably adjustable parts for simultaneously actuating the latter, and means connected to the revolute member and extending outwardly through the slot in the side wall of the base unit for actuation by the operator.

5. In a radio receiving set, a base having a supporting plate and having a casing supported above the plate to provide clearance therebe-

tween, a member enclosed by the casing and mounted for rotation in a plane substantially parallel to the plane of the plate, a plurality of condensers mounted in the casing in concentric relation to the axis of rotation of the member and respectively operatively connected to the member for simultaneous actuation by said member, and a control element operatively connected to the member and extending outwardly through the clearance provided between the plate and casing.

6. In a radio receiving set, a base unit having a supporting plate and having a casing provided with a bottom wall, means for supporting the bottom wall of the casing in vertically spaced relation to the supporting plate, a plurality of condensers mounted in the casing in concentric relation to the vertical center line of the casing, a member supported between the bottom wall of the casing and plate for rotation and having its axis coinciding with the vertical center line of the casing, means operatively connecting the member to each of the condensers for simultaneously actuating the latter, and a ring also supported between the bottom wall of the casing and plate for rotation about the axis of said member and having the periphery thereof projecting beyond the casing for convenient manipulation by the operator.

7. A radio receiving set comprising, in combination, a base, a frame structure, means for supporting said frame structure in spaced relation above the base, radio apparatus carried by said frame structure including a rotatably adjustable element, a rotatable control member for said element concentric with said base and located between said base and frame structure, and a casing enclosing said frame structure and carried thereby.

8. A radio receiving set comprising, in combination, a base, a frame structure comprising vertically extending parts connected at their lower ends by a transverse part, means for supporting said transverse part in spaced relation above said base, radio apparatus carried by said frame structure including a rotatably adjustable element mounted on said transverse part, a rotatable control member for said element located between said transverse part and said base, and a casing concentric with said control member enclosing said frame structure and carried thereby.

9. A radio receiving set comprising, in combination, a base, a casing disposed about a vertical axis, means for supporting said casing spaced above said base, radio apparatus mounted within said casing including a condenser mounted in the lower part of the casing and having a rotatably adjustable element, and a rotatable control member concentric with said casing and located between said casing and base, said control member being operatively connected to said element.

10. A radio receiving set comprising, in combination, a base, a generally round casing supported by and above said base, radio apparatus within said casing including a rotatably adjustable element, and a rotatable control member for said element located below said casing and concentric therewith, said control member extending adjacent the periphery of the casing whereby it may be readily manipulated.

DANIEL J. CROWLEY.
